JAMES BALL, OF NEW YORK, N. Y.

Letters Patent No. 78,353, dated May 26, 1868.

IMPROVEMENT IN ENVELOPE-MACHINES.

The Schedule referred to in these Letters Patent and making part of the same.

TO ALL WHOM IT MAY CONCERN:

Be it known that I, JAMES BALL, of 115 and 117 William street, New York, county and State of New York, have invented a new and useful Improvement in Envelope-Machines; and I do hereby declare that the following is a full, clear, and exact description thereof, which will enable those skilled in the art to make and use the same, reference being had to the accompanying drawings forming part of this specification, in which drawings—

Figure 1 represents a longitudinal vertical section of this invention.

Figure 2 is an end view of the same.

Figure 3 is a plan or top view of the same.

Figure 4 is a detached view of the folding-wing, which acts on the seal-flap.

Similar letters indicate corresponding parts.

This invention relates to certain improvements in envelope-machines, of that class in which the gum is applied to the seal-flaps of the blanks just before the same are carried into the folding-mechanism.

The invention consists—

First, in the arrangement of a revolving gummer, provided with a suitable projection, and moving at a different speed from the table, which supports the pile of blanks, in combination with this reciprocating table, in such a manner that the gummer, in passing over, will smoothly gum the sealing-flap.

Second, in giving to the revolving gummer a compound rising and falling and revolving motion, in such a manner that the same is depressed on the pile of blanks, and caused to revolve thereon for the purpose of applying the gum, and then raised clear of the pile of blanks and brought in contact with the gumming-rollers, where it is again revolved, for the purpose of taking up the requisite supply of gum.

Third, in the arrangement of a cam-stop and weight or spring, in combination with the shaft of the revolving gummer, in such a manner that by the combined action of the cam-stop and weight or spring, the pinions on the shaft of the revolving gummer are always held in the required position to drop in gear with the appropriate pinions or racks.

Fourth, in the arrangement of an automatic self-adjusting clamp, to act on the pile of blanks, and retain the same firmly in position while the gum is applied to any portion of the first or top blank in the pile, and to release the same, and permit the top blank being carried off by the pickers at the proper intervals.

Fifth, in giving to the pile of blanks a motion under the gummer and picker, in such a manner that said pile is alternately brought under the revolving gummer, which applies gum to the seal-flap, and then under the picker, which applies gum to the lower flap, and raises the blank up to be carried off by the conveyer.

Sixth, in the arrangement of an automatic stop-motion, whereby the picker and gummer are stopped, and retained in such a position that they do not interfere with the operation of putting in new work.

Seventh, in the arrangement of distinct strips, catching over the edges of the creasing-box, and constructed so that the same can be set to correspond to any variation or defect in the knife or in the blanks fed to the folding-mechanism.

Eighth, in the arrangement of detachable heels on the folding-wings, in combination with one or more set-screws, in such a manner that said wings can be made to act on the body of the envelope with more or less pressure while the edges are not pressed, and that envelopes of more or less thickness can be made, to suit the demand of the trade.

Ninth, in the arrangement of spiral carriers or worm-screws, for the purpose of carrying the envelopes along, and retaining them free from pressure, until the gum on the seal-flaps has had time to dry.

Tenth, in the combination of two or more sets of spiral carriers or worm-screws, running in opposite directions, in such a manner that the envelopes are delivered from one set of carriers to the other, and that the same are retained by said carriers a sufficient length of time to allow the gum on the seal-flap to dry.

Eleventh, in increasing the pitch of the threads at the receiving-ends of the spiral carriers, to facilitate the entrance of the envelopes.

Twelfth, in the arrangement of a separator, acting at suitable intervals on the envelopes, while the same are sustained by the spiral carriers, and serving to prevent the seal-flap of one envelope from adhering to the body of the next succeeding envelope.

Thirteenth, in the arrangement of a reciprocating conveyer to carry the envelopes from one set of spiral carriers to the other.

Fourteenth, in the arrangement of a transparent panel or pane in the receiving-table, so that the operator is enabled to watch the spiral carriers, and the mechanism connected with them, and to correct any irregularities occurring in the motion of the envelopes through said spiral carriers before any injury is produced.

A represents the frame of my machine, which is made of cast iron, or any other suitable material, and which supports the fixed bed, B, and the movable table, C. On this movable table rests a platform, D, being hinged to the table by a pivot, α , which passes through one end of the same, and being provided with a thumb-piece or lip, b , connected to its other end, so that by pulling the thumb-piece said platform can be turned in or out. This hinged platform is intended to receive and support the pile of blanks, which are held in the proper position by studs, c , rising from the platform, and which are introduced when the platform is turned out. When the platform is turned in, and occupies its working position, the blanks could not be introduced except at much loss of time.

When the platform is turned in, it is locked by the latch d^1 , which is pivoted to the front edge of the movable table, and which also forms the main element of the stop-motion, as will be presently explained.

The table C is fitted in suitable ways in the frame A, and a reciprocating motion is imparted to it by means of a cam, d , which is mounted on the driving-shaft e , and acts on an arm, f , that extends from a rock-shaft, g , which has its bearings in the rear part of the frame A. This rock-shaft connects, by two arms h , and rods i , with the table, as shown in figs. 1 and 3.

Above the table C rises a plate, E, which rests on suitable standards rising from the frame A, and this plate forms the support for two gum-boxes, F, F', best seen in figs. 1 and 3. Each of these gum-boxes is provided with a roller, j or j' , to which a continuous revolving motion is imparted by belts, k , k' , from the driving-shaft e . Close to the roller j , in the gum-box F, is a secondary roller, l , which turns freely in its bearings, and receives a revolving motion by frictional contact with the roller j , so that the gum taken up by this last-named roller is transferred to the roller l . From this roller the gum is transferred to the revolving gummer G, which is mounted on the shaft m .

This shaft has its bearings in slides n , to which a rising and falling motion is imparted by the combined action of springs o^1 and of arms o , which extend from a rock-shaft, p , which derives its motion from a cam, q , on the driving-shaft.

On the shaft m are mounted two pinions, r , r^1 , and a pulley, s , on which winds a cord, t , carrying a weight, t^1 , (for which a spring may be substituted, if desired,) and from the hub of which extends a tappet, u . When the shaft m is permitted to follow the action of the weight t , the tappet u is brought up against a stop, u^1 , projecting from one of the slides n , and by these means the pinions r , r^1 are held in such a position that when the slides n rise, the pinion r will engage correctly with a pinion, v , and when the slides descend, the pinion r^1 will engage correctly with a toothed rack, w . The pinion v is mounted on a stud, which is fastened in a bracket, v^1 , that is secured to the plate E, and it gears into a pinion, v^1 , which is mounted on the arbor of the gum-roller j , and revolves with the same, and when the pinion r drops into gear with the pinion v , a partial revolving motion is imparted to the gummer G, causing its surface to roll against the distributing-gum roller l , and thereby said revolving gummer is supplied with the requisite amount of gum. While the gummer G is thus revolved, the cord t is wound up on the pulley s , and as soon as the slides descend far enough to throw the pinion r out of gear with the pinion v , the weight t^1 drops down and throws the gummer G in the proper position to transmit its gum to the first blank of the pile on the platform D, and in order to bring said pile under the revolving gummer, the table C, with the platform, moves out to its extreme position. As the revolving gummer descends, the pinion r^1 drops into gear with the toothed rack w , which is fitted into the table C, and which is supported by springs, so that it can yield to the pressure of the pinion, and recede, until the gummer strikes the pile of blanks.

At the moment the table begins to move in towards the folding-mechanism, the gummer is made to revolve on the first blank by the action of the toothed rack w on the pinion r^1 , so as to transmit its gum to the seal-flap, and the pinion r^1 is so proportioned that the circumferential velocity of the gummer is greater than the velocity of the reciprocating table, so that a wiping motion is produced, whereby the transmission of surplus gum to the flap is prevented. After this object has been accomplished the slides n rise, the pinion r^1 disengages from the rack w , and the gummer is carried back to its original position by the weight t^1 .

While the revolving gummer acts on the pile of blanks, said pile is subjected to the action of a clamp, x , which is composed of two fingers, extending from vertical rods, which slide up and down freely in sockets in the table C. The lower ends of these rods bear on brackets y , which extend from the slides n , and as these slides rise, the clamp is raised clear of the pile of blanks, so as not to interfere with the action of the pickers H, but when the slides descend, the clamp sinks down by its own gravity, and bears on the pile of blanks, retaining the same firmly in position, while the revolving gummer takes effect.

The pickers H are raised by means of an arm, z , which extends from the plunger-rod o^2 , and they descend by their own gravity until they strike the pile of blanks, the arm z being made to work in a slot so that its motion is not limited by that of the pickers.

When the pickers have arrived in their highest position, (which is the case while the revolving gummer transmits its gum to the seal-flap,) the distributing-gum roller l^1 of the gum-box F', is moved out in such a manner that it rolls along under the pickers and transmits the requisite supply of gum to the picker-faces. To

effect this motion, said distributing-gum roller has its bearings in a carriage, b^2 , which moves between suitable guides on the top of the plate D, motion being imparted to it by rods c^2 , which extend from said carriage to a rod, d^2 , secured to arms e^2 , which are mounted on a shaft, f^2 , to which a rocking motion is imparted at the required intervals, by a cam on the driving-shaft. After the pickers have been thus supplied with gum, the roller l^1 recedes, the table C with the blanks moves in, and the pickers descend until they strike the pile of blanks. By these means gum is transmitted to the lower flap of the first blank, and when the pickers rise, said blank adheres to them, and is raised from the pile to the proper position to be received by the conveyer I.

In order to prevent the pickers and the revolving gummer from descending when the platform D is not in the proper working position, and particularly to obtain time for introducing new work, I have applied an automatic stop-motion, which will now be described. When the platform D is turned in to its working position, it is locked by the latch d , as has been previously stated. This latch is attached to the outer edge of the table C, by a pivot, g^2 , and it is operated by a button or thumb-piece, h^2 . When turned to its locking position, it rests on a stop, i^2 , secured in the lip b , which is connected to the platform D, and serves to move the same in or out. When the latch is reversed on its pivot, its tip strikes the end of the frame A, and its heel still projects over the lip b^4 , and prevents the platform D being moved until the table C has reached the inner end of its stroke. At that point the tip of the latch d drops into a notch in the frame, and the heel of said latch releases the lip b^4 , leaving the platform D free to be moved out from under the plate E. At the same time a small plate, k^2 , which is secured to the table C, has arrived under a stop, l^2 , which projects from the inner surface of one of the slides n , and by these means the slides are prevented from following the action of their springs o^1 .

Simultaneously with this action, the inner edge of the table C bears on a spring-arm, m^2 , which extends from an arbor, n^2 , on which is mounted a toe, o^2 , and which is subjected to the action of a spring, p^2 . This spring has a tendency to throw the toe back, so that its point will clear a projection, q^2 , on the inner surface of the rod to which the pickers are secured. But if the table bears against the arm m^2 , the toe is thrown forwards so that it catches under the projection q^2 , and the pickers are prevented from descending. The platform D can now be turned out, and new work put in without stopping the main shaft of the machine, and after the platform has been readjusted, the latch d is turned back and the operation of the machine progresses, as heretofore described.

The conveyers I are constructed like those of any common envelope-machine, and they carry the blank which they take from the pickers under the creasing-plunger K. This plunger receives its motion from a suitable cam on the driving-shaft, and it forces the blank down through the upper creasing-box L, and delivers it on to the folding-table M. This table is supported by a rod, r^2 , which is pivoted to a rocking arm, s^2 , and by said arm it receives a rising and falling motion, causing it to pass up into the lower creasing-box N, to the position which it occupies in fig. 1, and then down to discharge the folded envelope, and as it descends it is tilted on the pivot which forms its connection with the rod r^2 , so that the folded envelope will slide off on the chute t^2 .

On the edges of the lower creasing-box are the folding-wings v^2 v^{2*} , and after the creased envelope has been delivered on the folding-table, these wings turn in in the proper order to produce the operation of folding. Said wings are mounted on oscillating-spindles or arbors, to which the required motion is imparted from the main shaft, and they are provided with adjustable heels w^2 , so that they can be made to act with greater or less force on the envelopes, while the edges are left unpressed, and envelopes of greater or less thickness can be produced to suit the demand of the trade.

The wing v^{2*} which acts on the seal-flap of the envelopes, is operated, like the other folding-wings, by a crank, x^2 , mounted on one end of its arbor, and as said wing turns down, this crank strikes a stop, y^2 , which consists of a screw, so that it can be adjusted, and that the folding-wing v^{2*} is prevented from pressing the seal-flap close down on the body of the envelope. By adjusting the stop y^2 , the distance to which the seal-flap is pressed down can be adjusted, (see fig. 4.)

The sides of the lower creasing-box N are adjustable, so that said box can be slightly increased or decreased, to correspond to any irregularity in the knives or to any defect in the blanks.

The chute t^2 is perforated with two slots, to admit fingers u^2 , which extend from the top end of a lever, v^2 , that receives a vibrating motion by the combined action of a cam on the driving-shaft, and of a spring, w^2 . As the fingers u^2 come in contact with the envelope sliding down over the chute, they push the same into the first set of spiral carriers O.

This set consists of one or more pairs of worm-screws, each pair containing one right and one left-hand screw, placed parallel to each other, and made to revolve in such a direction that they carry the envelopes delivered to them down. The upper end of each carrier is provided with a screw-thread, x^2 , of increased pitch, so that the envelopes on dropping down from the chute are caught and delivered to the threads of the carrier, and the speed of the carriers is such that they complete one revolution while the folding-mechanism completes one envelope. The envelopes delivered to the spiral carriers are therefore separated by the intervening screw-threads, and they are carried down without being exposed to the slightest pressure, which might have a tendency to cause the seal-flaps to adhere to the bodies of the envelopes. It happens sometimes, however, that the seal-flap of one envelope catches, bears against the body of the next succeeding envelope, and adheres to it by small drops of gum projecting over the edge of said seal-flap, and I have therefore applied a separator, y^2 , which consists of an arm extending from an upright shaft, z^2 , to which a rocking motion is imparted by the combined action of a spring, a^2 , and of a cam, b^3 , which is mounted on the upper end of the gudgeon of one of the spiral carriers. This separator sweeps through between the several envelopes, and separates the seal-flaps if they should happen to adhere to the bodies of the succeeding envelopes.

An arm, c^2 , extending from the upper part of the shaft z^2 , assists in causing the envelopes to arrive in the

On reaching the bottom end of the carriers O, the envelopes are discharged upon the conveyer d^3 , to which a reciprocating motion is imparted by the action of the lever v^2 . By this conveyer one envelope after the other is delivered to the second set of spiral carriers O'. These carriers are constructed similar to the carriers O, but they revolve in such a direction that the envelopes delivered to them are carried up. Each of the carriers O' is provided with a screw-thread, e^3 , of increased pitch at its bottom end, so that the same are enabled to receive the envelopes from the conveyer d^3 without failure. On reaching the top ends of the carriers O', the gum on the envelopes has dried, and the envelopes can be put up in packages without delay. For this purpose a table, P, is attached to the end of the frame A, at such a height that the envelopes, on arriving at the top ends of the carriers O', can be readily counted off, taken out, placed on said table, and put up as desired. The table P is provided with a transparent pane, f^3 , so that the operator is enabled to watch the action of the carriers, and to see that no disorder takes place as the envelopes pass through said carriers.

By these means an envelope-machine is obtained, which gums the seal-flaps as well as the lower or end-flaps, and which completes the envelopes, so that the operator has nothing to do but to keep the requisite supply of blanks in the machine and to take the finished envelopes out.

What I claim as new, and desire to secure by Letters Patent, is—

1. The arrangement of a revolving gummer, G, having a different velocity from the table which supports the blanks, in combination with the reciprocating table C, substantially as and for the purpose described.
2. Giving to the revolving gummer a positive compound rising and falling and revolving motion, substantially as and for the purpose described.
3. The cam u , stop u^1 , and weight or spring t , in combination with the pinions r r^1 , on the shaft of the gummer G, substantially as and for the purpose set forth.
4. The self-adjusting clamp x to act on the pile of blanks, substantially as and for the purpose described.
5. Giving to the pile of blanks a motion under the gummer G and picker H, substantially as and for the purpose set forth.
6. The arrangement of an automatic stop-motion, composed of the latch d , and notch in the frame A, in combination with the gummer and picker, and with the platform D supporting the blanks, substantially as and for the purpose described.
7. The arrangement of distinct strips N, catching over the edges of the lower creasing-box, and attached thereto by set-screws, substantially as and for the purpose set forth.
8. The heels w^2 attached to the folding-wings v^2 v^{2*} , by one or more set-screws, substantially as and for the purpose described.
9. The spiral carriers O, to carry the envelopes along, and retain them free from pressure until the gum has dried, when arranged substantially as described.
10. The combination of two or more sets of spiral carriers O O', running in opposite directions, substantially as and for the purpose set forth.
11. Increasing the pitch of the screw-threads at the receiving-ends of the spiral carriers O O', substantially as and for the purpose described.
12. The separator c^3 , in combination with the spiral carriers, substantially as and for the purpose set forth.
13. The reciprocating conveyer d^3 , in combination with the spiral conveyers O O', constructed and operating substantially as and for the purpose described.
14. The arrangement of a transparent panel or pane, f^3 , in the receiving-table P of the envelope-machine, substantially as and for the purpose set forth.

JAMES BALL.
